(57) CLAIM

The ornamental design for a semicircular stylized Christmas tree, as shown and described.

DESCRIPTION

FIG. 1 is a perspective view of a semicircular stylized Christmas tree showing my new design;

FIG. 2 is a front elevation view thereof;

FIG. 3 is a top plan view thereof;

FIG. 4 is a bottom plan view thereof; and,

FIG. 5 is a side elevation view thereof.

Broken lines shown in the drawings illustrate unclaimed environmental subject matter and form no part of the claimed design.

All surfaces not shown form no part of the claimed design.
